CHARLES K. DUNLAP, OF HARTSVILLE, SOUTH CAROLINA, ASSIGNOR TO SONOCO PRODUCTS COMPANY, OF HARTSVILLE, SOUTH CAROLINA, A CORPORATION OF SOUTH CAROLINA

SPOOL

Application filed May 18, 1932. Serial No. 612,111.

This invention relates to spools adapted for use in supporting thread packages in the textile industry, and particularly to spools designed and intended for use in supporting and carrying packages of silk or rayon thread.

Many types of spools suitable for use as cores or supporting bodies for thread packages have heretofore been designed or suggested and have been placed in actual use. Progress in the textile industry, however, has rendered large numbers of types of spools heretofore found useful obsolete for various reasons. The spool which comprises the present invention was developed to supply the advanced needs of the industry, particularly those throwsters, knitters, or weavers who deal with silk and rayon threads, with an inexpensive, light-weight, simple, and moisture-proof spool which, when operatively positioned upon a creel, will rotate with a minimum of frictional loss.

A spool constructed in accordance with the present invention is rugged and durable, being practically unbreakable, will not distort when subjected to moisture laden atmospheres, will not rust in any material or important part, and may be manufactured of such relatively inexpensive materials that it need only be used but once and thereafter discarded.

One embodiment of the invention, selected for disclosure by way of example, is illustrated in the accompanying drawing, in which:

Figure 1 is a perspective view of the completed spool; and

Figure 2 is an axial section therethrough.

The spool comprises, as do all spools of this type, three principal portions, the tubular body indicated at 10 and the two heads indicated at 11, 11. The heads are positioned at the ends of the body and are concentric therewith, as is usual practice, and means is provided for securing each head to the adjacent end of the body. I prefer to form the tubular body of paper, a suitable strip or sheet of paper being wound upon itself, by means of the mandrel, to form a tube at least several plies in thickness, the several

convolutions of which are secured together by a suitable adhesive. A waterproof cement or adhesive is preferably employed, and the paper tube after completion may be otherwise treated, if desired, to increase its resistance to the penetration of moisture and thereby obviate any liability to distortion due to swelling of the paper.

The spool heads or end discs are also preferably formed of paper, and, in the original fabrication of these members, a plurality of sheets of paper, such as kraft paper, may be superposed one upon the other and thereafter formed into a single unit by heavy pressure. Following the application of heavy pressure, the discs thus formed are preferably coated with a waterproofing and strengthening material such as bakelite. This coating prevents penetration of moisture into the fibers of the paper and thereby eliminates the possibility of subsequent distortion due to swelling of the fibers, at the same time imparting increased smoothness and mechanical strength so that the discs as secured in position have ample strength for the purpose intended, being well able to resist shocks incident to transportation and rough handling.

In forming the spool heads, it is preferred that each of them shall have a peripheral bead 11' upon one face and a groove 11" formed in the opposite face, into which groove the end of the tubular body 10 may project. The means for securing the body and heads together will now be described.

Secured within each end of the tubular body 10 is a wooden plug 12, such plug being preferably provided with external threads 13 so that it may be inserted by a turning operation and cannot be thereafter longitudinally pulled out, the threads 13 biting into the inner layer of the paper tube 10. If desired, adhesive may also be employed to secure a firm bonding of the external surface of each plug with the inner surface of the tube.

Each plug is also centrally perforated or apertured, such aperture being preferably cylindrical and having, intermediate its ends, a shoulder 14 facing inwardly. The cylindrical aperture in each plug registers with the cylindrical axial aperture of the associated

disc when these members are properly assembled, and extending through these registering apertures is a metallic eyelet 15 preferably fabricated of copper. Encircling the projecting end of each eyelet 15 is a washer 16 of steel or like material. The ends of the eyelet are upset or headed over as shown, the upset portions engaging, respectively, the shoulder 14 and the washer 16. A number of 10 nails or like members are indicated at 17. These nails extend through the end discs and into the adjacent plugs. They serve as additional means for securing the end discs to the plugs and also perform the function of 15 preventing relative rotation of the plugs and heads 11, which relative rotation is not resisted by the eyelets 15. The heads of the nails are covered by the washers 16.

The various parts just described may be 20 assembled in different ways, but I preferably assemble the plugs, heads, and securing means into units in preliminary operations and thereafter insert the plugs in the ends of the tubular body. The assembly of each plug, 25 end disc, and securing means can be rapidly effected by means of suitable machines, and the assembly of these completed units with the tubular body can obviously be quickly and easily accomplished. The completed 30 spool is composed, for the most part, of paper, and the paper parts have great strength and are, at the same time, light in weight and cost very little. The metallic parts are comparatively few in number, light in weight, and low 35 in cost.

While I prefer to fabricate the spool exactly as shown in the drawing and as above described, minor changes in the design and arrangement of its component parts may be 40 made without departure from the spirit and scope of the invention.

Having thus described the invention, what is claimed as new and desired to be secured by Letters Patent is:

45 1. In a spool of the type described, in combination, a cylindrical body, plugs secured in the ends of said body, said plugs being centrally apertured, disc-like heads at the ends of said body and centered on the axis thereof, 50 said heads being axially perforated, eyelets projecting through the registering apertures of the plugs and heads respectively to secure the heads to the plugs, and a plurality of securing members disposed around each eyelet, each such member being positioned in part in the associated plug and in part in the adjacent head, thus preventing relative rotation of the head and plug.

60 2. In a spool, a cylindrical paper body, a disc-like paper head at the end of the body and arranged concentrically thereto, said head having a cylindrical axial aperture, and means for securing the head to the body comprising a wooden plug secured within the 65 end portion of the body, said plug having

an aperture registering with the aperture formed in the head, a cylindrical metal eyelet extending through said registering apertures, and a washer encircling the outer end of said eyelet and lying flat against said head, 70 the ends of the eyelet being upset to engage oppositely facing surfaces of the plug and head respectively.

In testimony whereof I hereunto affix my signature.

CHARLES K. DUNLAP.
